INVENTOR

EDWARD D. MYERS

Charlesville, Va.

UNITED STATES PATENT OFFICE.

EDWARD D. MYERS, OF SHELBY, MICHIGAN.

KIT CARRIER.

Application filed September 19, 1921. Serial No. 501,638.

To all whom it may concern:

Be it known that I, EDWARD D. MYERS, a citizen of the United States, and a resident of the city of Shelby, in the county of Oceana and State of Michigan, have invented certain new and useful improvements in a Kit Carrier; and I do hereby declare that the following is a full, clear, and exact description of the same, reference being had to the accompanying drawings and to the numerals of reference marked thereon, which form a part of this specification.

This invention relates more particularly to an improved type of a kit carrier or casing having drawers therein for carrying automobile parts and further being provided with exterior removable curtains or aprons adapted to carry a set of tools.

It is an object of this invention to provide a portable automobile tool and part holder adapted to be used as a seat if desired while repair work is being done.

It is a further object of the invention to provide a tool kit carrier wherein a flexible tool carrying apron is adapted to be removably engaged on the exterior of the device for use and further adapted to be rolled up and placed within a carrier drawer and locked therein.

Another object of the invention is the construction of a kit carrier having drawers or trays and exterior flaps for carrying extra automobile parts and tools respectively in a convenient manner, said kit carrier having a handle to permit carrying of the holder from place to place.

It is an important object of this invention to provide a tool and part carrier of simple and effective construction, and embracing a divided casing having slidable trays or drawers in the interior thereof, and provided on the exterior with a flexible apron or covering for carrying tools, said apron adapted to be removed and rolled up to fit within the casing.

Other and further important objects of this invention will be apparent from the disclosures in the drawings and specification.

The invention (in a preferred form) is illustrated in the drawings and hereinafter more fully described.

On the drawings:

Figure 1 is a side elevation of a kit carrier embodying the principles of this invention and showing the tool apron remov-

ably secured in place on the exterior of the kit carrier casing.

Figure 2 is a transverse section taken on line 2—2 of Figure 1.

Figure 3 is a longitudinal section taken on line 3—3 of Figure 2.

Figure 4 is an enlarged fragmentary detail section taken on line 4—4 of Figure 3, showing the locking bar in locked position.

Figure 5 is a fragmentary detail section taken on line 5—5 of Figure 4.

As shown on the drawings:

The kit carrier comprises a housing or casing embracing a base 1, a top 2 narrower than the base, and inclined side walls 3 connecting the base and said top. A partition wall 4 is secured within the upper portion of the casing to divide the same into an upper chamber 5 and a lower chamber 6. Slidably engaged in the upper casing chamber 5 is an upper drawer or tray 7 having transverse partitions 8 therein dividing the tray into a plurality of compartments. Each end of the tray 7 is provided with a handle or knob 9 to permit the tray to be drawn out through either end of the casing. The tray 7 is provided with an opening 10 which is adapted to register with an opening 11 in the partition 4 when the tray is in normal position within the casing.

Rigidly secured within the lower portion of the casing is a wall or support 12 upon which a lower drawer or tray 13 is adapted to slide. The base plate 14 of the lower drawer 13 is wider than the drawer and rests on the support 12 as illustrated in Figure 2. The lower drawer base plate 14 is provided near one side with an aperture or opening 15. The lower drawer 13 is provided with a removable cover 16. Each end plate of the drawer 13 is provided with a handle or knob 17. The end plates of the drawers 7 and 13 are adapted to close up the ends of the casing when the drawers are in normal position.

For the purpose of locking the drawers 7 and 13 within the casing a locking bar 18 is slidably mounted within the casing adjacent the inner surface of one of the casing side walls 3. The upper end of the locking bar 18 projects upwardly through the partition opening 11 and through a slot or opening in the casing top member 2. Rigidly secured or integrally formed on the locking bar 18 is an upper locking hook or latch 110

19 and a lower locking hook or latch 20 which are respectively disposed below the partition 4 and the support 12. The upper portion of the latch bar 18 is provided with 5 an aperture or opening to permit the bail 21 of a pad lock 22 to be engaged therethrough when the latch bar has been elevated into locking position as illustrated in Figure 4. The upper and lower drawers are thus 10 locked within the casing with the upper latch 19 engaged through the registering openings 10 and 11, while the lower latch 20 engages through an opening in the support 12 and through the opening 15 of the 15 lower drawer base plate 14.

To permit the kit carrier to be conveniently carried, a strap handle 23 is provided. One end of the strap handle 23 is rigidly secured to one end of the upper casing member 2. The other end of the strap handle is 20 provided with a button 24 adapted to be removably engaged on a snap fastener 25 secured on one end of the upper casing member 2.

25 In Figure 2 the dotted circle 26 represents a rolled up flexible tool holder disposed within the lower casing compartments 6 and resting on the lower drawer cover 16. If desired the tool holder may be deposited within the 30 lower drawer 13 instead of on the cover thereof. The tool holder is made of flexible material such as canvas or other suitable fabric and comprises a middle or top portion 26 adapted to fit on the top of the upper casing member 2. The ends of the holder top portion 26 are provided with buttons 27 adapted to be removably snapped upon snap fasteners 28 secured on the top of the upper casing member 2. Integrally 35 formed or rigidly secured to the longitudinal margins of the holder strip or top portion 26 are two flexible fabric aprons or flaps 29, the outer corners of which are equipped with snap buttons 30 adapted to be removably engaged on snap fasteners mounted on the 40 lower corners of the casing inclined side walls 3. When the tool holder is unrolled and mounted on the casing, the flexible aprons are held in place flat against the outer 45 surfaces of the casing side walls 3 by the snap fasteners 30. Sewed or otherwise secured to each of the aprons 29 is an upper piece of fabric and a lower piece of fabric. The upper and lower pieces of fabric are 50 sewed to afford a plurality of upper and lower tool pockets 31 and 32 respectively for carrying tools 33. With the flexible aprons lying flat against the inclined side walls 3 of the kit carrier casing the tools in 55 the various pockets 31 and 32 are permitted to lay flat against the aprons. Due to the tapered shape of the kit carrier casing, the tools on both sides of the kit carrier can be seen from above when the flexible tool holder 60 is unrolled and stretched or fastened over the 65 top and sides of the casing in position for use.

When the tool holder is mounted in place the detachable end of the handle 23 is, of course, first unfastened. The device may be 70 used as a seat if desired when repair work is being done. The flexible tool holder may be readily removed from the casing and rolled up in compact form and placed within the casing as shown in dotted lines in Figure 2. 75

With the drawers and the tool holder positioned within the casing, the drawers may be readily locked against removal by simply pulling the locking bar 18 upwardly and engaging the padlock bail 21 through the opening in the upper end of the locking bar. The padlock 22 may then be locked with the upper and lower latch hooks 19 and 20 engaged in the respective drawer openings 10 and 15 to prevent sliding of the drawers. 80 85 The padlock may be released by means of a key in the ordinary manner when access to the interior of the kit carrier is desired by an authorized person.

I am aware that various details of construction may be varied through a wide range without departing from the principles of this invention, and I therefore do not purpose limiting the patent granted, otherwise than necessitated by the prior art. 90 95

I claim as my invention:

1. A kit carrier, comprising a casing, a removable flexible covering for the top and sides of said casing, means for removably attaching said covering to said casing with 100 its sides constituting aprons to cover the casing sides, and tool holders on said aprons, said covering operating when in position to afford ready access to all the tools, and being adapted to be folded for storage within 105 said casing.

2. In a device of the class described, a casing, drawers therein, a removable flexible covering for the top and sides of said casing, means for removably attaching the middle 110 portion of said covering to the top of said casing with the sides affording aprons to cover the casing sides, tool holders on said aprons, and a handle attached to said casing to permit the device to be carried. 115

3. A portable kit carrier comprising a casing, a handle thereon, drawers slidably engaged in said casing, a flexible tool holder adapted normally to be carried in rolled up form in said casing and further adapted to be unrolled and secured over the exterior of the casing for use, and means for simultaneously locking said drawings within the casing. 120

4. A portable tool kit carrier comprising a case having inclined side walls, a handle for the casing having one end rigidly secured to the casing and the other end detachably connected therewith, and a flexible tool carrying covering adapted to be rolled up 125 130

in compact form to fit within the casing when not in use and further adapted to be unrolled and secured over the casing in position to permit convenient access to the 5 tools carried thereby.

5. A portable tool kit carrier comprising a casing having inclined sides, drawers slideable in said casing having openings in the bottom thereof, a locking bar slidably engaged in said casing, latch hooks formed thereon, said locking bar adapted to be elevated to bring the latch hooks into engagement with the drawer openings to hold the drawers locked against removal from the 10 casing, and a lock engaged with the locking bar to hold the same locked in an elevated locking position.

6. A kit carrier comprising a portable casing, a handle thereon for carrying the casing, snap fasteners on the exterior of the 20 casing, a flexible covering adapted to be removably engaged over the top and sides of the casing, buttons thereon adapted to removably engage said snap fasteners to hold the flexible covering stretched in place, and 25 pockets secured on said covering for carrying tools.

In testimony whereof I have hereunto subscribed my name in the presence of two subscribing witnesses.

EDWARD D. MYERS.
